GEARING FOR GRAIN DRILLS

Royce R. Borngraeber, Horicon, Wis., assignor to
John Deere Van Brunt Company, Horicon,
Wis., a corporation of Wisconsin

Application November 25, 1949, Serial No. 129,391

3 Claims. (Cl. 74—325)

1

The present invention relates generally to agricultural implements and more particularly to planting implements, such as grain drills and the like.

The object and general nature of the present invention is the provision of new and improved drive gearing between the driving and driven shafts of a grain drill or other implement. More specifically, it is an important feature of this invention to provide a speed-change mechanism between the driving and driven shafts of a grain drill, which includes two reversible and interchangeable compound gear members, with new and improved supporting means for the reversible and interchangeable compound gears, whereby the desired change of driving ratios may be secured with a minimum number of relatively simple and inexpensive parts and with a minimum time required to effect the desired changes.

More particularly, it is an important feature of the present invention to provide a new and improved gear hanger and new and improved gear-supporting studs or bearing members attachable in different and definitely determined positions on the gear hanger so as to definitely and positively dispose the compound gear members in the proper position to mesh not only with each other but also with the associated driving and driven gears of the grain drill.

These and other objects and advantages of the present invention will be apparent to those skilled in the art after a consideration of the following detailed description, taken in conjunction with the accompanying drawings, in which:

Figure 1 is a fragmentary perspective view of a portion of a grain drill in which the principles of the present invention have been incorporated.

Figures 2 and 3 are side and top views of the gear hanger.

Figures 4 and 5 are fragmentary perspective views, showing two out of a possible five different positions of the compound gears on the gear support.

Figure 6 is a sectional view taken generally along the line 6—6 of Figures 2 and 5.

Figure 7 is a perspective view of one of the gear-supporting studs or bearing members.

Referring now more particularly to Figure 1, the grain drill in which the principles of the present invention have been incorporated is indicated in its entirety by the reference numeral 1 and comprises a seed box 2 mounted on a frame 3 which is made up of a plurality of transverse angles 4 and end angles 5, together with suitable braces and the like, generally of conventional

2

construction so far as the present invention is concerned. The grain or seed box 2 is mounted on the rear portion of the frame 3 by suitable end brackets 7 fixed by bolts 8 to the frame end members 5. The grain drill frame 3 is supported by suitable ground wheels (not shown), at least one of which is connected by a driving chain or the like to a drive sprocket 9 which is fixed to the outer end of a jackshaft 10. The jackshaft 10 serves as a drive shaft for the seeding mechanism of the grain drill which conventionally includes a feed shaft 12 and a feed shaft gear 13. The grain drill also includes a drive shaft gear 14 which is controllably connected to be driven from the jackshaft 10 by clutch means, a portion of which is shown at 15 in Figure 1.

A change-speed mechanism, with which the present invention is more particularly concerned, serves to connect the feed shaft and drive shaft gears 13 and 14 and will now be described.

A gear hanger 20 is adapted to be fixed to the grain drill frame 3 in a position adjacent the gears 13 and 14 and comprises a generally vertically disposed plate section 21 having at its rear end a pair of tapped openings 23 and 24 into which a pair of machine bolts 25, extending through openings 26 in the vertical flange 27 of the associated frame angle 5, are adapted to be threaded, as best shown in Figure 3. The forwardmost tapped opening 24 is disposed in an outwardly extending boss 28 carried by the plate section 21 of the hanger, the rear end of the latter being bent laterally outwardly and then rearwardly, as shown in Figure 3, to form an attaching lug 29. The plate section 21 of the hanger 20 is also provided with a pair of laterally outwardly extending locating lugs 31 and 32 which are adapted to overlie the horizontal flange 33 of the frame end member 5. The rear end of the attaching lug 29 is beveled, as shown at 34 in Figure 2, so as to clear the head of the rear bolt 8 that fixes the end bracket to the frame 3.

The drive is transmitted from the driving gear 14 to the driven gear 13 by means of a pair of reversible and interchangeable compound gear members 35 and 37 (Figure 4) which are detachably mounted on the gear hanger 20. The compound gear member 35 comprises a smaller gear section 41 and a larger gear section 42, and the other compound gear member 37 is of similar construction, including a smaller gear section 43 and a larger gear section 44. Preferably, the gear section 43 is smaller than the gear section 41 and the gear section 44 is larger

than the gear section 42. In one form of the present invention the gear section 41 has eighteen teeth, the gear section 42 has twenty-five teeth, and the gear sections 43 and 44 have fifteen and twenty-eight teeth, respectively.

As best shown in Figures 1 and 2, the plate section 21 on the gear hanger 20 includes raised portions 51 and 52, each of which is provided with a plurality of sockets, the section 51 having sockets 53, 54 and 55 while the other section 52 is provided with sockets 56, 57, 58 and 59. Each socket is generally polygonal in configuration with its intermediate sockets merging into and blending with the end sockets. However, each socket includes a pair of diametrically opposed portions, being in the preferred form of the present invention opposite corner portions of a square. One of the compound gear members 35 and 37 is adapted to be fixed to one or the other of the gear hanger portions 51 and 52 while the other compound gear member is adapted to be mounted on the other gear hanger portion. To this end, I provide a gear-receiving stud 63, best shown in Figures 6 and 7, for each of the compound gear members 35 and 37. Each stud 63 comprises a tubular member including a generally cylindrical gear-receiving section 64 having at one end a gear-receiving flange 65 extending generally radially beyond the cylindrical section 64 and at the other end a smaller squared socket-entering section 66. Two of such studs 63 are provided, and the squared portion 66 of either may enter and be non-rotatably connected to the hanger in any of the hanger socket sections 53-59, inclusive. Each of the square sockets 53-59 is provided with a tapped opening 69 which is adapted to be aligned with a bolt-receiving opening 71, 72 formed in each stud 63. Each stud is adapted to be fixed in position in any one of the sockets 53-59 by means of a machine bolt 73, the threaded end of which is adapted to be screwed into the opening 69 in the associated socket. The outer end of each of the gear-receiving studs 63 is provided with a tapped opening 74 to receive a lubricant fitting, the interior of the stud being enlarged, as at 75, to form a lubricant reservoir.

It will be seen from Figure 1 that the driven and driving gears 13 and 14 are carried by the grain drill in a spaced-apart relation that is fixed for any particular drill, and that the driving gear 14 is of sufficient width to be meshed with either of the gears 35 or 37, irrespective of whether the larger gear section thereof is disposed adjacent the other side of the grain drill or facing inwardly thereof, as shown in Figures 4 and 5, respectively. It will also be seen from Figures 4 and 5 that either of the compound gears 35 and 37 may be disposed with either one or the other of its gear sections in mesh with the feed shaft or driven gear 13. However, as will be readily understood, the disposition of one or the other of the compound gear members 35 and 37 in a position to have its smaller or its larger section meshing with the driven gear 13 calls for the support of its stud 63 at different distances radially from the axis of the feed shaft 12. Likewise, the disposition of the other of the compound gear members so as to have one or the other of its gear sections in mesh with one of the gear sections of the compound gear meshing with the driven gear 13 also calls for the disposition of the other gear-supporting stud 63 at different radial distances from said one compound gear.

member and also from the axis of rotation of the drive gear 14. The first mentioned variation in the support of the compound gear member adjacent the driven gear 13 is provided by the three sockets 53, 54 and 55, while the last mentioned variation in the support of the other compound gear member is provided by the four sockets 56-59.

In order to provide an easily understood and conveniently available way of determining the positions of the two gear-supporting studs 63 on the hanger 20 for any desired driving ratio between the gears 13 and 14, I prefer to form letters A through G on the gear hanger 20 adjacent the sockets 53-59, respectively, the gear members 35 and 37 also carrying the same letters A through G arranged in the following manner: The letters A and F are formed on the outer side of the larger gear section 44 of the compound gear 37 while the inner face, adjacent the smaller gear section 43, carries the letter G. The outer face of the larger gear section 42 of the compound gear member 35 carries the letters B and E while, at the other side of the gear member 35, the outer face of the smaller gear section 41 carries the letters C and D. The hanger-carried letters and the gear-carried letters therefore form indexing means whereby the operator may easily and quickly ascertain the positions in which the studs 63 are to be attached to the gear hanger for the desired arrangement of the compound gear members 35 and 37.

With the reversible and interchangeable gear members and the different stud-receiving sockets on the gear hanger available as shown in the drawings, five different speed ratios are possible, two being shown by way of illustration in Figures 4 and 5.

Referring first to Figure 4, it will be seen that in this particular selection of gear ratios, the gear 37 is so disposed that its larger section 44 is in a position to mesh with the driving gear 14, in which position of the gear 37 the letter G faces inwardly of the drill, which renders the inner face easily observable by the operator arranging the drill for operation. To bring the gear 37 to the position shown in Figure 4, therefore requires that the stud 63 for the gear 37 be disposed in the forwardmost socket 59 of the gear hanger 20, the socket 59 being adjacent the letter G on the gear hanger. The chosen position of the other compound gear member 35, in the gear ratio selection assumed, being that in which the letters C and D are showing, the stud 63 for the compound gear member 35 will therefore be disposed in the socket 55, which is opposite the letter C. The fact that in this position of the gear member 35 the letter D is showing is of no consequence since the set of sockets 53-55 do not have the letter D associated therewith. The speed ratio afforded by the arrangement of the gears 35 and 37 in Figure 4 is fairly high being only slightly less than the speed of the driving shaft or jackshaft 10. If a slightly slower speed of the feed shaft 12 is desired, the compound gear members 35 and 37 may be arranged as shown in Figure 5. To secure the change from the gear arrangement shown in Figure 4 to the gear arrangement shown in Figure 5 all that it is necessary to do is to reverse each of the gears 35 and 37. When reversing the gear 35, for example, it will be seen that the smaller section 41 is to mesh with the gear driven gear 13. This requires a repositioning of the gear-

supporting stud 63. In this position of the gear 35, the letters B and E are showing. This instructs the operator, therefore, to reposition the studs 63 for the gear 35 by removing the machine bolt 13, placing the squared end 66 of the stud 63 in the socket 54, which is the socket designated by the letter B, and then reinserting and tightening the machine bolts 13. The fact that in this position of the gear 35 the letter E also shows is of no consequence since the group of sockets 53-55 does not have the letter E associated therewith. Since the stud 63 for the gear 35 has been repositioned, it will also be necessary to reposition the stud 63 for the gear 37. In the new position of the latter gear the letters A and F are showing. This instructs the operator to place the stud 63 in the socket 58, which is opposite the letter F in the second group of sockets 56-59. The socket 58 is so located that when the stud 63 is fixed therein, the member 37 is in the proper position to have its larger section 44 mesh with the larger section 42 of the gear 35 and with the driving gear 14 on the jackshaft 10.

It is believed that the other possible positions of the compound gear members 35 and 37 need not be illustrated. It may be mentioned, however, that three additional arrangements are possible, namely, (a) smaller gear section 41 and compound gear member 35 meshing with larger gear section 44 of compound gear 37 and the smaller gear section 43 of the latter compound gear member meshing with the driven gear 13; (b) the larger gear section 42 of compound gear member 35 meshing with the larger gear section 44 of the compound gear member 37, with the smaller compound gear section 43 meshing with the driven gear 13; and (c) the larger gear section 44 of the compound gear member 37 meshing with the smaller gear section 41 of the compound gear member 35, with the larger gear section 42 of the latter compound gear member meshing with the driven gear 13.

The seating of the squared end 66 of each of the gear-supporting studs 63 in the associated squared socket in the gear hanger serves to hold the associated gear stud against rotation, the gear stud being firmly fixed to the gear hanger by the tightening of the associated machine bolt 13. This effectively fixes the stud or bearing member for each of the compound gear members to the associated gear hanger so that rotation of the bearing member relative to the hanger is prevented, whether the gear members be rotated in one direction or the other. Since the gear hanger sockets have tapped openings receiving the threaded ends of the stud-attaching machine bolts, the connection of the studs to the gear hanger is facilitated since the operator is not required to manually hold nuts or the like on the outer side of the gear hanger while screwing the stud-attaching bolts into position. Since the gear hanger is firmly and rigidly fixed to the frame of the grain drill and the various stud-receiving sockets 53-59 an integral and fixed part of the hanger, it will be seen that the gear sections of both of the compound gear members, in whatever position they may be mounted, are always in proper and accurate mesh with one another and with the associated driven and driving gears 13 and 14.

The forwardmost end of the gear hanger member 20 is provided with a laterally outwardly extending lug 80 (Figures 3-5) which at its outer end bears against a wheel supporting plate 81. 75

The engagement between the lug 80 and the wheel support 81, to which a ground wheel (not shown) is connected, cooperates with the bolts 25 in holding the gear hanger in position.

5 While I have shown and described above the preferred structure in which the principles of the present invention have been incorporated, it is to be understood that my invention is not to be limited to the particular details shown and described above, but that, in fact, widely different means may be employed in the broader aspects of my invention.

What I claim, therefore, and desire to secure by Letters Patent is:

15 1. In a grain drill having a frame and a feed shaft gear and a drive shaft gear journaled thereon, the improvement comprising speed-change mechanism adapted to connect said gears and including a pair of compound gears, each 20 having gear sections of different diameters, a pair of gear studs, one for each of said compound gears, each stud including a gear-receiving cylindrical bearing section and an axially arranged polygonal boss at one end smaller than the diameter of said bearing section, a gear hanger having two sets of polygonal sockets spatially arranged to receive said polygonal bosses of both of said studs in a plurality of positions and to hold said studs against rotation, the spatial arrangement of said studs accommodating reversal 25 and interchange of said compound gears while disposing them in mesh with each other and with said shaft gears, means for fixing said studs in selected sockets, and means for connecting said gear hanger with said frame.

2. In a grain drill having a frame and a feed shaft gear and a drive shaft gear journaled thereon, the improvement comprising speed-change mechanism adapted to connect said gears and 30 including a pair of compound gears, each having gear sections of different diameters, a pair of gear studs, one for each of said compound gears, each stud including a gear-receiving cylindrical bearing section and a non-circular hanger-engaging section, a gear hanger having two sets of non-circular sockets spatially arranged to receive the non-circular sections of both of said studs in a plurality of positions, each of said non-circular sockets including generally opposed 35 40

45 stud-positioning portions adapted to engage a stud and hold the same in a given position on the gear hanger, thereby accommodating reversal and interchange of said compound gears while disposing them in mesh with each other and 50 with said shaft gears, means for fixing said studs to said hanger, and means for connecting said hanger to said frame.

3. In a grain drill including a feed shaft gear, a drive shaft gear and speed-change means connecting said gears including a pair of reversible and interchangeable compound gears adapted in any one of a plurality of different positions to intermesh with each other and to mesh with said gears to connect the latter in driving relation:

60 the improvement comprising a pair of gear receiving studs, a gear support having two sets of stud-receiving portions, cooperating locating means and said studs including non-rotatable interconnectable parts on said studs and said stud-receiving portions, the latter being spatially disposed on said gear support so as to accommodate reversal and interchange of said compound gears while disposing them in mesh with each other and with said shaft gears, and means for 65 70

fixing said studs optionally to selected stud-receiving portions of said gear support.

ROYCE R. BORNGRAEBER.
